Primary Examiner — Darlington Ly*Assistant Examiner* — Katherine A Holbrow(74) *Attorney, Agent, or Firm* — Cantor Colburn LLP(57) **CLAIM**

The ornamental design for a display screen or portion thereof with graphical user interface, as shown and described.

DESCRIPTION

FIG. 1 is a front view of a display screen or portion thereof with graphical user interface, showing our new design; and, FIG. 2 is an enlarged view of the encircled portion in FIG.

1.

The outermost evenly-spaced broken lines depict a display screen or portion thereof that form no part of the claimed design. The remaining evenly-spaced broken lines depict portions of the graphical user interface that form no part of the claimed design. The dot-dash broken lines encircling portions of the drawing disclosure illustrated in an enlargement form no part of the claimed design.

1 Claim, 2 Drawing Sheets(56)
